(57) CLAIM

The ornamental design for a notebook computer, as shown and described.

DESCRIPTION

FIG. 1 is a top, front and right-side perspective view of a notebook computer showing our new design with the computer in the closed position;

FIG. 2 is a front elevational view thereof;

FIG. 3 is a top plan view thereof;

FIG. 4 is a right-side elevational view thereof;

FIG. 5 is a left-side elevational view thereof;

FIG. 6 is a rear elevational view thereof;

FIG. 7 is a bottom view thereof;

FIG. 8 is a top, front and right side perspective view of the notebook computer with the computer in the open position;

FIG. 9 is a front elevational view thereof;

FIG. 10 is a top plan view thereof;

FIG. 11 is a right-side elevational view thereof;

FIG. 12 is a left-side elevational view thereof; and,

FIG. 13 is a rear elevational view thereof.
